VOLTAGE REGULATING RELAY
Robert J. Sullivan, Wayne, N.J., assignor to Westinghouse
Electric Corporation, Pittsburgh, Pa., a corporation of
Pennsylvania

Filed Aug. 26, 1966, Ser. No. 575,396
7 Claims. (Cl. 317—142)

This invention relates generally to relaying apparatus and more particularly to apparatus which energizes a relay in a timed manner.

An object of this invention is to provide a time-actuated self-locking relaying apparatus.

A further object of this invention is to provide a time delay apparatus which times both the time period that the actuating signal is applied and the time period that the actuating signal is removed.

Another object is to provide a timing apparatus which will time out in a lesser time period than the full time period of the timer when an initial signal is applied for a lesser time interval than the full timing interval, the initial signal is interrupted for an interval which is less than the time period that the initial signal is applied, and a signal is thereafter reapplied.

A further object is to provide such an apparatus having an energy storage device which is charged and discharged through impedances of substantially the same magnitude.

Other objects of this invention will be apparent from the description, the hereinafter appended claims and the drawing, the sole figure of which schematically illustrates a voltage controlling network for a transmission line embodying the invention.

Referring to the drawings by characters of reference, the numeral 1 indicates generally a transmission line having a local end portion 1A at which the voltage and current sampling equipment are located and a remote portion 1B at which a load 2 is located. The apparatus located at line portion 1A provides the load 2 with a regulated substantially constant voltage.

The voltage at the load 2 is sensed at the local end 1A of the transmission line 1 by combining voltage and current quantities derived by means of a current transformer 4 and a voltage or potential transformer 6. The primary winding 7 of the current transformer 6 and the primary winding 8 of the transformer 6 are connected to the transmission line 1 at the local line portion 1A. The secondary winding 10 of transformer 6 and the secondary winding 11 of the current transformer 4 supply the required voltage and current signals to a compensating network 12 which compensates for the line drop between the portions 1A and 1B.

The compensating network 12 comprises a transformer 14, a transactor or mutual inductor 15, and a resistor network 20, and a variable resistor 22. The output electrical quantity of the secondary winding 10, is modified by the voltage established in the output winding 18 of the mutual inductor 15 and in the resistor network 20 whereby the magnitude of the quantity supplied to the primary winding 16 of the transformer 14 is equal to the voltage at the local line portion 1A minus the voltage drop in the transmission line 1 between the local end portion 1A and the remote portion 1B.

The secondary winding 11 of the current transformer 4 is connected across the primary winding 26 of the mutual inductor 15 through a portion of the resistor network 20 whereby the output quantity of the series connected transactor 15 and resistor network 20 decreases the output voltage of the winding 10 by an amount which is electrically equivalent in phase and magnitude to the voltage drop between the local portion 1A and the remote portion 1B of the transmission line 1.

2

The secondary winding 28 of the transformer 14 is connected across the alternating current input terminals 30 of a fullwave rectifying bridge network 32 through a current limiting resistor 34. The direct current output terminals 36 of the network 32 are connected to input terminals 38 and 40 of a bridge network 42 through a filter network 43 to energize the network 42 with an electrical quantity having a magnitude which is a direct function of the potential at the load 2.

The filter network 43 may take any of a number of forms. Preferably, it takes the form, as illustrated, in which a first filter capacitor 44 is connected between the output terminals 36 of the rectifier network 32, a second filter capacitor 45 is connected directly between the bridge network terminals 38 and 40 and resistors 46 and 47 are connected in parallel with each other between one of the rectifier network terminals 36 and the bridge terminal 38. A thermistor 48 is connected in series with the resistor 47 to compensate the network for temperature changes.

The bridge network 42 comprises two parallel arms interconnecting the terminals 38 and 40. The first of these arms includes, in series connection, a resistor 50, the resistive element of a potentiometer 52 and a resistor 54. The other arm includes a resistor 59 and a Zener diode 58. The bridge network 42 further is provided with a pair of output terminals 60 and 62; the terminal 60 being connected to the movable arm 63 of the potentiometer 52 and the output terminal 62 being the common connection of the resistor 56 and the Zener diode 58.

The magnitude of the breakdown voltage of the Zener diode 58 and the magnitudes of the resistance of the resistor 50, 54 and 56, the resistive element of the potentiometer 52 and the adjustment of the movable arm 63 on the resistor element of the potentiometer 52 are selected so that when the voltage supplied to the load 2 is within the selected bandwidth, the magnitude of the electrical quantity applied across the input terminals 38 and 40 of the bridge network will maintain the output terminals 60 and 62 at substantially the same potential. If the potential at the load 2 exceeds this desired voltage bandwidth, the potential between the input terminals 38 and 40 will increase and the potential of the terminal 60 will elevate above that of the potential of the output terminal 62. The opposite effect on the potential between the output terminals 60 and 62 occurs when the voltage supplied to the load 2 decreases below the desired voltage bandwidth. A suitable bandwidth is ± 1 volt from the desired voltage.

Any form of amplifier responsive to the direction of flow of an input quantity applied thereto and having a suitable output quantity for operating a suitable voltage raising or voltage lowering mechanism (illustrated by labeled VOLTAGE RAISE DEVICE and VOLTAGE LOWER DEVICE) may be connected to the output terminals 60 and 62 of the bridge network 42. A preferred form of such amplifier is as illustrated and comprises a pair of magnetic amplifiers 64 and 66.

The magnetic amplifiers 64 and 66 include saturable cores 68A-68B and 70A-70B respectively. Each core is preferably of a material having a substantially rectangular hysteresis loop (two cores each). The set 68 of two cores 68A and 68B is provided with a control winding 72 and a bias winding 74 both of which are wound over both cores 68A and 68B. Similarly, set 70 of cores 70A and 70B is provided with a control winding 76 and a bias winding 78 both of which are wound over both cores 70A and 70B. The gate winding of the magnetic amplifier 64 comprises a pair of winding portions 80A and 80B which are individually located on the cores 68A and 68B respectively. Likewise, the gate windings of the magnetic amplifier 66 comprises winding portions 82A and 82B which are individually located on the cores 70A and 70B.

The magnetic amplifiers 64 and 66 are energized respectively from the center-tapped secondary windings 84 and 86 of a transformer 88 having its primary winding 90 energized from a suitable source of alternating current potential which may be, as illustrated, the secondary winding 10 of the transformer 6. The center tap of the winding 84 is connected to the movable contact of a resistor 92 which connects the two corresponding terminals of the winding portions 80A and 80B. Similarly, the center-tap connection of the winding 86 is connected to the movable contact of a resistor 94 which connects corresponding terminals of the winding portions 82A and 82B. The dotted terminals of the winding portions 80A and 80B are connected to the end terminals of the winding 84 and similarly the dotted terminals of the gate winding portions 82A and 82B are connected to the end terminals of the secondary winding 86.

The transformer 88 is provided with an additional secondary winding 96 which supplies power for the relaying networks 110R and 110L and for the bias windings 74 and 78. The end terminals of the winding 96 are connected to the alternating current input terminals 97 of a full-wave bridge rectifier 98. The positive direct current output terminal 99 of the network 98 is connected through a resistor 100 to a positive direct current bus 102. The negative output terminal 103 of the full-wave bridge 98 is connected directly to the negative bus 104. The voltage between the buses 102 and 104 is controlled by means of a Zener diode 105 connected in series with a pair of diodes 106 and 107 between the positive bus 102 and the negative bus 104. The output of the rectifier bridge 98 is smoothed by a filter capacitor 108 connected between its direct current output terminals 99 and 103.

The magnetic amplifiers 64 and 66 are individually provided with output busses 64A and 66A. The potentials which exist between the negative bus 104 and the output busses 64A and 66A are the output quantities of the amplifiers 64 and 66 respectively. The bus 64A is connected through a pair of oppositely poled diodes to the opposite ends of the resistor 92 and through a diode 112R to one terminal 113R of a capacitor 114R. Similarly, the bus 66A is connected through oppositely poled diodes to the ends of the resistor 94 and through a diode 112L to one terminal 113L of a capacitor 114L. The opposite terminals of the capacitors 114R and 114L are connected to the bus 104, which is connected to the adjustable taps of the resistors 92 and 94. Preferably, the busses 64A and 66A are prevented from becoming appreciably negative with respect to the bus 104 by diodes 115R and 115L. Resistors 116R and 116L may be used to limit the positive excursions of the busses 64A and 66A.

The bias winding 74 and 78 of the magnetic amplifiers 64 and 66 are connected in series between the direct current bus 104 and an adjustable tap 117 of a voltage divider 118 connected between the buses 102 and 104. The adjustment of the tap 117 and the consequent magnitude of current through the bias windings 74 and 78 determines the voltage bandwidth established at the load 2. The control windings 72 and 76 are connected in series between the output terminals 60 and 62 of the bridge network 42 which controls the direction and magnitude of current through these windings 72 and 76. The windings 72, 74, 76, 78, 80A, 80B, 82A and 82B are polarized with respect to each other such that when current flows through the control windings 72 and 76 as a consequence of the potential of terminal 62 being positive with respect to that of terminal 60, the bus 64A be energized and the bus 66A remain deenergized and conversely when the potential of terminal 60 is positive with respect to terminal 62.

The relay operating networks 110R and 110L are identical and the same reference characters will be used for like elements in each thereof. In the specification, in certain instances for clarity, the suffix R or L will be added

to the numerals to make it clear which of the networks 110R or 110L is being referred to.

Each network 110 includes an energy storage device which may take the form of a capacitor 122 having one of its terminals connected to the negative bus 104 and its other terminal 123 connected through resistors 124, 126 and 128 to the positive bus 102. The timing interval of the network 110 is determined primarily by the magnitude of the resistance of the resistor 126 which controls the rate at which charging current flows to and flows from the capacitor 122. To control these intervals, the common terminal 130 of the resistors 126 and 128 is connected to the negative bus 104 through the emitter cathode circuit of a transistor 132. The base of transistor 132 is connected to the common terminal 133 the resistors 134 and 136 of a voltage dividing network comprising the resistors 134, 136 and 138. The terminal 133 is normally positive with respect to the negative bus 104 whereby base current normally flows through the base emitter circuit of the transistor 132 and maintains the transistor 132 conducting to prevent the flow of charging current to the capacitor 122. Conducting of transistor 132 also completes a time controlled discharge circuit for the capacitor 122 through the resistors 124 and 126, and will hold the capacitor 122 in substantially completely discharged conditions thereafter.

The voltage dividing networks 134, 136 and 138 is provided with a second output terminal 140 which is located intermediate the resistors 136 and 138. The terminal 140 is selectively connected through the emitter-collector circuit of the transistor 120 to the negative bus 104. When the voltage supplied to the load 2 is of the desired magnitude, the magnetic amplifiers 64 and 66 have no output potential, the capacitors 114 are discharged and no base current will flow from either of the terminals 113R or 113L through the current limiting resistors 119 and to the transistor 120. With transistor 120 in its non-conducting state, the potential of the terminal 133 is maintained elevated with respect to the bus 104 and base current flows in the transistor 132. The resulting emitter-collector conduction of transistor 132 prevents the flow of charging current to the capacitor 122. If the capacitor 122 is partially charged at the time the transistor 132 is rendered conducting, any partial charge therein discharges through the resistor 126. When the potential supplied to the load 2 is below or above the desired potential bandwidth, the magnitude amplifiers 64 or 66 render one or the other of the transistors 120R and 120L, as the case may be, conducting thereby rendering one or the other of the normally conducting transistors 132R or 132L blocked to permit charging current to flow to the one of the other of the capacitors 122R or 122L.

The potential appearing across the capacitor 122 is applied between the emitter and the base b_1 of a voltage sensitive switch 142 which preferably is, and is illustrated as being, a unijunction transistor. The base b_2 of the unijunction transistor 42 is connected to the positive bus 102 through a resistor 143, the base b_1 is connected to bus 104 through the energizing winding of a magnetic relay 144, and the emitter e is connected to the terminal 123.

The relay 144 is shown as having normally open contacts 145 and normally open contacts 146. A diode 147 may be connected in shunt with the energizing winding of the relay 144 to pass reactive current. The emitter of the unijunction transistor is connected through a diode 149, the back contacts 146 and resistor 150 to the positive bus 102. If desired, the common connection 152 of the resistors 124 and 126 may be connected through a diode 154 to the common connection 156 of the back contact 146 and resistor 150. Also, the common connection 130 may be connected through a diode 158 to the common connection 159 of the diode 158 and the back contacts 146.

It is believed that the remainder of the details of con-

struction may best be understood by reference to the operation hereof which is as follows:

Assuming an instant in which the voltage supplied to the load 2 is within the desired bandwidth, the potential across the bridge terminals 38 and 40 will cause the output terminals 60 and 62 to be at substantially the same potentials and not enough current will flow through the control windings 72 and 76 to actuate the amplifiers 64 and 66.

With the magnitude of current through the control windings 72 and 76 below a desired minimum value and the bias windings 74 and 78 energized, as described, the potential of the output buses 64A and 66A of the magnetic amplifiers 64 and 66 will be substantially that of the negative bus 104. Under these conditions neither of the transistors 120R nor 120L receives base drive and the transistor 132R and 132L conduct to prevent the flow of charging current to the capacitors 122R and 122L. The charge on the capacitor 122 will be less than the critical charge required to fire the unijunction transistors 142, the transistors 142 will not conduct to energize the corresponding relay 144 and neither the voltage raise nor the voltage lower devices will be actuated.

Assuming that the voltage applied to the load 2 decreases to a value below the bandwidth value, the potential between the terminals 38 and 40 of the bridge network 42 will decrease and the potential of the terminal 62 will become greater than that of the terminal 60. Under these conditions, control current flows through the windings 72 and 76 in a direction such that the winding 76 establishes flux which aids that provided by the bias winding 78. The magnetic amplifier 66 remains in its off condition.

The direction of this current flow is such that the control winding 72 establishes flux which opposes that established by the bias winding 74 by an amount sufficient to cause the magnetic amplifier 64 to become effective to energize its output bus 64A. Energization of the bus 64A causes the capacitor 114R to charge and elevate its terminal 113R, the transistor 120R is rendered conductive to terminate base current flow to and thereby terminate conduction of the transistor 132R. When transistor 132R becomes nonconducting, charging current flows to the capacitor 122R at a rate determined primarily by the magnitude of the resistance of the resistor 126.

If this low voltage condition at the load 2 continues without interruption for the timing period of the timer 110R, the voltage across the capacitor 122R rises to a critical value and the unijunction transistor 142R conducts. Conduction of the transistor 142R energizes the relay 144R which thereupon closes its front and back contacts 145R and 146R.

Closure of the front contacts 145R energizes the voltage raise device whereby the voltage supplied to the line 1 is increased through apparatus (not shown) well known to those skilled in the art. The closure of the back contacts 146R establishes a holding circuit for the relay 144R which extends from the positive bus 102 through resistor 150R, the now closed back contact 146R, diode 149R to the emitter of the unijunction transistor 142R. This ensures that once the relay has been energized it will remain energized until deenergized from a suitable external source.

When the voltage at the load 2 is again within the selected bandwidth, the output bus 64A of the magnetic amplifier 64 will no longer be energized, the capacitor 114R will quickly discharge and the transistor 120R will revert to its blocked condition. The transistor 132R reverts to its conducting condition and completes a circuit through the diode 158 which effectively interrupts the current flow through the diode 149 resulting in the discharge of the capacitor 122 through diodes 154 and 158. This decreases the potential of the emitter e of the unijunction transistor 142R and it becomes non-conducting. The relay 144R opens its contacts 145R and 146R whereupon the network 110R reverts to its initial state and the volt-

age raise device terminates any further increase in voltage of the line 1.

Now assume a condition in which the time interval during which the potential supplied to the load 2 was below the selected bandwidth for a time period less than the critical timing period of the raise network 110R. The return of the voltage within the bandwidth causes the transistor 120R to block and the transistor 132R to reconduct. When transistor 132R reconducts, the charge which accumulated in the capacitor 122R during the blocked period of the transistor 132R discharges at a rate determined primarily by the magnitude of the resistor 126R through the emitter collector circuit of the transistor 132R. If the voltage supplied to the load 2 remains within the desired bandwidth for a sufficient time interval, the charge on the capacitor 122R will completely or substantially completely drain away through the transistor 132R and the timer will be reset to time out its maximum time interval.

If, however, prior to the complete discharge of the capacitor 122R the voltage at the load 2 again decreases to a magnitude below the desired bandwidth, the transistor 120R will again be rendered conducting and block the transistor 132R. This interrupts the flow of discharge current and initiates the flow of charging current from and to the capacitor 122R through the resistor 126R. Since a partial charge remained in the capacitor 122R, the time required for the capacitor 122R to reach its critical value and fire the unijunction transistor 132 will be less than the full timing operation of the network 110R. The magnitude of this reduced timing interval will depend upon the length of the period that the voltage at the load 2 was initially below the desired bandwidth.

Preferably the current required to operate the relay 144 is of sufficient magnitude so that when the unijunction transistor 142 conducts and the winding of the relay 144R is energized, the added current flow through the resistor 100 reduces the current flow through the Zener diode 105 and the diodes 106 and 107. This results in a lesser voltage drop across the diodes 105-107 and results in a decrease in the voltage applied between the buses 102 and 104. The current through the bias controlling windings 74 and 78 is a direct function of the bus voltage and the decrease in bus voltage reduces the bias current to permit the amplifier to energize its output bus at a lesser magnitude of voltage change at the load 2. This eliminates hunting 11 and ensures a positive actuation of one of the relays 144 which are actuated.

If the voltage at the load 2 increases above the bandwidth voltage, the magnetic amplifier 64 will not energize its output bus 64A since the flux caused by the current flow through the winding 72 will aid that produced by the winding 74 to the direction which occurred when the voltage at the load 2 was below the bandwidth level. However, the flux produced by the control winding 76 will be in opposition to that produced by the bias winding 78 and the amplifier 66 will energize its output bus 66A and the network 110L will be actuated at the end of the timing period. The lower relay network 110L operates exactly in the same manner as described in connection with the raise relaying network 110R and a further detailed description is not believed necessary.

The voltage regulating apparatus may be tested by the expedient of inserting desired portions of the resistance 22. This in effect decreases the voltage applied to the transformer 14 which provides the same effect as a decrease at the load 2. The magnitude of this decrease may be observed by the voltmeter 160. Any change in the voltage produced by the change in the setting of resistor 22 should be compensated for by the voltage controlling network 110 to return the voltage measured by the voltmeter 160 substantially to its initial reading.

Since numerous changes may be made in the above-described apparatus and different embodiments of the invention may be made without departing from the spirit

thereof, it is intended that all matter contained in the foregoing description or shown in the accompanying drawings, shall be interpreted as illustrative and not in a limiting sense.

What is claimed and is desired to be secured by U.S. Letters Patent is as follows:

1. In a relaying apparatus, a relay having a current consuming control element and circuit controlling means, a pair of electrical energy input terminals, a pair of buses, a plurality of impedance elements, a Zener diode, first circuit means connecting said Zener diode between said buses, second circuit means including a first of said impedance elements connecting said buses to said input terminals, an energy storage element, a unijunction transistor having first and second bases and an emitter, third circuit means connecting said bases between said buses, fourth circuit means connecting said storage element in series with a second of said impedance elements between said buses, fifth circuit means connecting said emitter to said fourth circuit means at a location intermediate said storage element and said second impedance element, a switching means, sixth circuit means connecting said switching means in shunt with said storage element and said second impedance element, and a seventh circuit means connecting said emitter to one of said buses and including said circuit controlling means.

2. The combination of claim 1 in which said fourth circuit means includes a third of said impedance elements connected in series with said second impedance element intermediate said second impedance element and said one bus, said sixth circuit being connected between the other of said buses and a point in said fourth circuit means intermediate said second and third impedance means.

3. The combination of claim 2 in which there is provided an eighth circuit connecting said emitter to said other bus, said eighth circuit including said switching means.

4. The combination of claim 2 in which there is provided a magnetic control device having a bias flux setting winding and a control winding and an output winding, means connecting said bias winding between said buses for energization with a current proportional to the voltage between said buses, and means connecting said output winding to said switching means for actuation of said switching means by said output winding, and control means connected to said control winding for energization of said control winding, said control means being effective to energize said control winding to produce flux in said

5

magnetic device in a direction opposite to that of the flux produced by said bias winding.

5. A timing network for a relay comprising a relay having a control element and circuit controlling means, first and second energy supplying buses, an energy storage element, at least one impedance element, a plurality of unidirectional current conducting devices, a voltage sensitive switch having a first and second and third terminals, said switch being characterized by the fact that it becomes conductive solely when the potential between its said third terminal and its said first terminal is above a predetermined critical percentage of the potential between its said first and its said second terminals, a first circuit connecting said first and second terminals to said first and second buses respectively, a second circuit connecting said storage element and a first of said impedance elements in series between said buses, said storage element being located intermediate said first impedance element and said first bus, a third circuit connecting said third terminal to said second bus and including a first of said unidirectional devices and said circuit controlling means, switch means connected in shunt with said storage element and said first impedance element, and a fourth circuit connecting said third terminal to a point in said second circuit which is intermediate said storage element and said first impedance element, said control element being connected to be energized in response to conduction through said first terminal.

6. The combination of claim 5 in which said voltage sensitive switch is a unijunction transistor, said third terminal is said emitter of said transistor, said control element is in series circuit with said emitter.

7. The combination of claim 6 in which said second circuit includes a second of said impedance elements connected intermediate said first impedance element and said second bus, said switch means being a transistor.
